UNITED STATES PATENT OFFICE.

GEORGE SHEPHERD JOHNSON, OF BRAINERD, MINNESOTA.

SUCTION-BOX FOR PAPER-MAKING MACHINES.

1,375,517.

Specification of Letters Patent. Patented Apr. 19, 1921.

Application filed April 19, 1920. Serial No. 875,049.

To all whom it may concern:

Be it known that I, GEORGE S. JOHNSON, a citizen of the United States, residing at Brainerd, in the county of Crow Wing and 5 State of Minnesota, have invented certain new and useful Improvements in Suction-Boxes for Paper-Making Machines; and I do declare the following to be a full, clear, and exact description of the invention, such 10 as will enable others skilled in the art to which it appertains to make and use the same.

This invention relates to an improved suction box for use in connection with a paper 15 making machine and one object of the invention is to so construct the box that the suction through the box may be evenly distributed and excessive wear upon the felt prevented at any particular point. In suction boxes of the usual construction the suction above the exhaust pipe is greater than any other place in the box and therefore the felt at this point will be worn more than at other points whereas with this device the 20 objection is overcome.

Another object of the invention is to so construct the suction box that the suction may be confined to a space of approximately the width of the paper and to permit of adjustment according to the width of the 25 paper.

Another object of the invention is to so construct the box that the top or head thereof may be properly centered in the body portion of the box.

Another object of the invention is to so construct this box that the head may be formed of a plurality of sections which will be separately placed in the body of the box 40 and securely held in an assembled position.

Another object of the invention is to so construct this head that it may be easily built to the desired size, it simply being necessary to provide the proper number of intermediate sections according to the size of head desired.

Another object of the invention is to so construct the box that it may be easily and quickly taken apart for cleaning or repairs 45 when necessary and be readily reassembled.

This invention is illustrated in the accompanying drawings wherein:

Figure 1 is a top plan view of the improved suction box.

Fig. 2 is a longitudinal sectional view 55 through the box taken along the line 2—2 of Fig. 1.

Fig. 3 is a longitudinal sectional view 60 through the box taken along the line 3—3 of Fig. 2.

Fig. 4 is a transverse sectional view taken along the line 4—4 of Fig. 2.

Fig. 5 is a view showing the box in end elevation.

This improved box is provided with a 65 housing having a bottom 10 and side walls 11 which have their upper portions cut away from the inner faces of the walls thus providing a seat for the head indicated in general by the numeral 12. This head is formed 70 of a plurality of sections, the end ones 13 of which carry plates 14 which are engaged by the screws 15 threaded through openings formed in the end plates 16 closing the ends of the housing. The central sections 17 are 75 cut in the form of a wedge as shown in Fig. 1 and the intermediate sections 18 are cut to extend diagonally across the head as shown. Each of these intermediate sections has one side portion cut to provide slots 80 19 when the head is assembled, the slots extending diagonally so that they cover a relatively wide area as the felt passes over the suction box. The central sections 17 and the end sections 13 will at all times be used 85 and the proper number of intermediate sections 18 will be put in place according to the size of head desired. It will thus be seen that the size of the head can be easily varied according to the size of the box. In 90 order to slidably mount the head, the sections forming the same will be provided with notches 20 thus providing side grooves in which the strips 21 carried by the side walls fit. Therefore the head can be moved longitudinally between the side walls of the housing and can be properly centered and securely held in the desired position by means of the screws 15.

In order to properly distribute the suction 100 through the housing there has been provided a baffle plate 22 which is positioned in the housing at a point intermediate its height and rests upon the longitudinally support-

ing strips 23 and end blocks 24 positioned in the lower portion of the housing. This baffle plate is provided with a plurality of openings 25 which are grouped in the end portions of the plate. It should be noted that the central portion of this plate which will be located above the port 26 from which extends the exhaust pipe 27 will be unperforated and therefore the suction will be prevented from being excessive above the exhaust port. In this manner the suction will be evenly distributed throughout the width of the felt which passes over the suction box and there will be no danger of it being worn to a greater extent directly above the exhaust port than at any other point. It is also desired to have the suction confined to the width of the paper passing over the box and in order to do this there has been provided blocks 28 which are slidably mounted in the housing between the baffle plate 22 and the head 12. These blocks 28 are mounted upon the inner end portions of stems 29 which extend through the plates 16 and terminate in handles 30 so that the stems 29 may be easily grasped and the stems moved longitudinally thus changing the positions of the blocks in the housing.

When in use the box is assembled as shown and suction through the housing will be provided by means of an exhaust fan connected with the pipe 27. The blocks will be moved to the proper points according to the width of the paper and as the paper moves over the suction box the proper action will take place due to the fact that the suction throughout the width of the box is of even strength. When it is desired to make any necessary repairs, the securing screws 31 which hold the plates 16 in place will be removed and the plates 16 can then be removed from the ends of the housing. The blocks 28 will be carried outwardly with these plates and the housing will be left open thus permitting the baffle plate 22 and the head to be easily and quickly removed. When the proper cleaning or repair has been made the device will be reassembled and the plates 16 then put back in place and secured. It will thus be seen that the suction box is so constructed that it can be easily and quickly taken apart and reassembled and further is so constructed that the suction through the same can be controlled.

55 What is claimed is:

1. A suction box comprising a housing open at its upper end, a head closing the upper end of the housing and provided with transversely extending slots converging toward the center of the housing, a suction pipe entering the bottom of the housing at approximately the center thereof, a baffle plate in the housing intermediate its height and having its end portions perforated and its central portion above the suction pipe

unperforated, and head blocks slidably mounted in the end portions of the housing between the baffle plate and the head of the housing for closing the openings in the end portions of the plate and housing. 70

2. A suction box comprising a housing having an outlet port in the intermediate portion of its bottom, a head closing the upper end of the housing and provided with diagonal slots extending transversely of the head, a baffle plate in the housing having its end portions perforated and its central portion unperforated, and means in the end portions of the housing between the plate and head for selectively closing the openings 75 80 in the end portions of the plate and head.

3. A suction box comprising a housing having a head provided with air inlet slots and having its bottom provided with an air outlet port intermediate its length, and a baffle plate positioned in the housing intermediate its height and having its end portions 85 perforated and its central portion above the outlet portion unperforated.

4. A suction box comprising a housing 90 having a bottom and side walls, a head for the housing provided with air passages and mounted between the side walls for longitudinal sliding movement, plates closing the ends of the housing, and adjusting means 95 for the head carried by the plates and engaging the head for imparting longitudinal movement to the head and retaining the head in a set position.

5. A suction box comprising a housing 100 having an outlet port in its lower portion and having a head provided with inlet openings, and a perforated baffle plate in the housing between the head and outlet port, the portion of the baffle plate directly above the outlet port being unperforated. 105

6. A suction box comprising a housing having side walls, a head positioned between the side walls and provided with air inlet openings, runner strips carried by the side 110 walls of the housing and fitting into grooves in the head to slidably mount the head, end plates for the housing, and set screws fitted through the end plates and engaging the ends of the head to adjust the position of the head and retain the head in a set position. 115

7. A suction box comprising a housing having its bottom provided with an air outlet port, the head for the housing provided with 120 air inlet openings, a baffle plate in the housing between the head and outlet port, the baffle plate being provided with air passages upon opposite sides of the outlet port, blocks for closing certain of the openings of the head 125 and baffle plate slidably mounted in the end portions of the housing between the head and baffle plate, and actuating rods for the blocks extending through the ends of the housing. 130

8. A suction box comprising a casing having an air outlet port, and a head for the housing formed of sections extending transversely and having their side portions cut to provide air inlet slots when the sections are in contacting relation.

9. A suction box comprising a housing having an outlet port, a head having inlet openings, a suction equalizing plate in the

housing between the head and outlet port, 10 and means adjustably mounted in the housing between the head and plate for selectively closing certain of the openings of the head.

In testimony whereof I have hereunto set 15 my hand.

GEORGE SHEPHERD JOHNSON.
